IRRIGATION APPARATUS

William M. Berg, New York, N. Y.

Application May 24, 1933, Serial No. 672,687

1 Claim. (Cl. 128—227)

This invention relates to irrigation apparatus, an object of the invention being to provide such an apparatus which may be securely held on a bowl so as to drain freely into the bowl and permit the user to regulate the flow of water while seated on the bowl.

A further object is to provide an apparatus of this character which can be manufactured and sold at a reasonably low price and which will 10 most efficiently perform the functions for which it is intended.

With these and other objects in view, the invention consists in certain novel features of construction and combinations and arrangements of 15 parts, all of which will be more fully hereinafter described and pointed out in the claim.

In the accompanying drawing,—

Figure 1 is a view in elevation of my improved apparatus showing the same in operative position 20 on a bowl, the bowl and its seat being shown in vertical section;

Figure 2 is a plan view taken on the line 2/2 of Figure 1; and

Figure 3 is an enlarged fragmentary view in 25 section on the line 3/3 of Figure 2.

1 represents a lavatory bowl and 2 an ordinary seat therefor. My improved apparatus includes a block 3 adapted to be positioned on the bowl 1 under the seat 2, and having a plurality of legs 30 4. I have shown the block 3 as having two of its legs 4 at the front and one at the rear of the block, and these legs bear against the outer and inner surfaces respectively of the bowl so as to hold the block against lateral displacement.

35 The block is securely clamped against movement by the seat 2. The block 3 is made with a transverse bore 5 for the reception of a tube 6. This tube at its inner end is bent at right angles, as shown at 7, and extends downwardly 40 and then upwardly constituting a curved portion 8, and the extremity is positioned centrally of

the bowl and is adapted to receive any suitable type of nozzle 9, in accordance with the use to which the device is to be put. I have illustrated a form of nozzle 9 which is used for irrigating the colon, and this is one of the important uses to which the device is put, although it may be used as any form of douche or spray desired.

The forward end of the tube 6 has an elbow 10 removably secured thereon to allow the tube to be effectually cleaned from time to time, and 10 this elbow 10 communicates with a vertical tube 11 having a manually operable valve 12 therein, with a handle on the valve in convenient reach of the operator. This tube 11 may be connected by a hose 14 with a supply tank or any suitable 15 source of supply, not shown.

In order to hold the inner nozzle supporting end of the tube against swinging movement the block 3 is provided with a notch 15 which receives the bent and downwardly projecting portions 7 and 20 8 of the tube 6.

By reason of the construction above described it is apparent that the parts may be separated, thoroughly cleaned, and sterilized if desired, and then reassembled. An apparatus of this character 25 enables the user to control the flow of liquid and permit a complete drainage into the bowl.

What I claim is:

An apparatus of the character described, including a member adapted to rest on a bowl, depending portions on the member engaging opposite faces of the wall of the bowl to hold the member against displacement, said member adapted to be clamped between the bowl and a seat, a tube extending through the member and 30 having within the bowl a downwardly and upwardly curved portion, the forward end of said tube adapted to receive a supply pipe, and a valve 35 in said supply pipe.
